SHAKING MECHANISM FOR FOURDRINIER MACHINES

Frank M. Sanger, Watertown, N. Y., assignor to
The Bagley and Sewall Company, Watertown,
N. Y., a corporation of New York

Application August 4, 1932. Serial No. 627,405

21 Claims. (Cl. 92—45)

This invention relates to certain improvements in mechanisms for effecting a shaking or vibratory movement of certain types of machines, and has been designed particularly for use with the web forming section of a Fourdrinier paper making machine or the like.

According to the present invention, a part of the web forming mechanism of such machines is supported so that it may have a horizontal shaking or vibrating movement sidewise of the machine, this movement being produced by a weighted rotating member or members, the pulling weight of which is supported off center, so that an unbalanced condition is produced. It has been found in practice that the centrifugal action of such an unbalanced weight sets up a vibration, the extent of which depends on the speed of rotation, the amount of pull of the weight, the radial distance of this weight from its center of rotation and the resistance to the vibratory movement produced, all factors which can readily be determined and controlled. The power required to effect this vibratory movement of the support is, with this arrangement, little, if any, greater than that required to revolve the unbalanced weight, provided the support is positively connected with and is arranged to be moved in timed relation with the weight.

The invention has for its especial object the provision of a shaking or vibratory frame for the web forming section of a Fourdrinier paper making machine in combination with a rotating unbalanced weight, so that an efficient shaking movement is imparted to the frame.

It is a further object of the invention to provide a construction in which the vibratory movement imparted to the frame is in a horizontal direction, any vertical vibratory movement of the frame being substantially eliminated.

It is a further object of the invention to provide a simple construction by which the vibratory movement imparted by the weight may be varied as desired within the limits of the mechanism.

It is a further object of the invention to produce a simple and compact mechanism for effecting these desired results, the parts of which are readily accessible for adjustment and repair.

With these and other objects not specifically referred to in view, the invention consists in certain novel combinations, parts and arrangement which will be described in connection with the accompanying drawings and the novel features pointed out in the claims hereunto appended.

In these drawings:—

Figure 1 is an end elevation, partly broken away and partly in section, of a preferred construction embodying the invention;

Figure 1a is a detail showing the motor connection and is a continuation of the right hand side of Figure 1;

Figure 2 is a view partly broken away and partly in section, the view being taken on the broken line 2—2 of Figure 1 looking in the direction of arrow X;

Figure 3 is a detail sectional view of the frame for supporting the web forming part of the Fourdrinier machine, the view being taken on the broken line 3—3 of Figure 1;

Figure 4 is a plan view, partly broken away, of the construction shown in Figure 1;

Figure 5 is a side elevation of the web forming part of a Fourdrinier paper making machine, showing the table rolls, the framing for supporting these, and the making wire, and

Figures 6, 7 and 8 are diagrammatic views showing the means employed for preventing vertical movement of the shaking frame of the machine in several modifications.

Referring now to these drawings and first to Figure 5, there is shown the web forming section of a Fourdrinier paper making machine the parts of which are suitably supported in standards 1, 1' of suitable configuration. This section includes a breast roll 2, a set of table rolls 3, and the making wire 4, this latter being endless and passing over a couch roll not shown, and tension rollers, one of which is shown marked 5.

These parts are supported in stationary side frames (Figure 1) 6, 7, but the table rolls and certain associated parts are supported on these side frames so as to have a horizontal vibrating movement sidewise of the stationary supporting frames. As shown, the bearings 8 of the table rolls are supported on a pair of shaking or vibratory frame members 9, 10 which in turn are mounted on flat springs 11, 12.

The stationary side frames 6, 7, before referred to, are, as shown, hollow and the springs 11, 12 are secured in these side frames and to the shaker frames in any suitable manner. As shown, the lower ends of the springs are secured by bolts 13 to the under side of the frames 5, 6, and the upper ends of the springs are secured to heads 14, having rounded ends 15, engaging in blocks 16 secured to the under side of the shaker frames 9, 10, the tops of the stationary frames 6, 7 being cut away, as shown at 17, to permit free movement of the springs.

To afford a strong rigid structure and to insure an even vibratory movement throughout the length of the shaker frames, these frames are tied together at a plurality of points. While this may be effected in various ways, in the particular construction illustrated these tie members are in the form of hollow tubes 18, 19, the ends of which are provided with extensions 20, 21 to which the shaker frames are bolted by bolts 22, these tubes partaking of the sidewise movement of the shaker frames 9, 10, before referred to. In the best constructions, so as to permit an adjustment or control of the vibratory movement given the shaker frames, as more fully hereinafter referred to, resilient means are provided which control the vibratory movement of these frames. The particular construction of these resilient means may be somewhat varied, but they will preferably be provided at a plurality of points so as to provide an even vibratory movement for the shaker frame section. As illustrated, secured as by bolts 23 to the outer sides of the stationary frames 6, 7 are recessed members or bonnets 24, 25, forming seats for one end of coiled springs 26, 27, these springs seating, at their other ends, in recesses 28 formed in the ends of the tie tubes 18, 19, before referred to. Passing through the bonnets, springs and tie tubes are adjusting rods 29, on the ends of which are hand adjusting wheels 30. These wheels operate left and right hand threaded members 31, 32, and through sliding collars 33 act to increase or decrease the tension on the springs 26, 27, two of the springs of each set being thus simultaneously adjusted. In accordance with the invention, there is provided a construction including an unbalanced weighted rotating member for effecting the shaking or vibratory movement of the shaking frames. In the best constructions, a plurality of sets of such mechanisms will be provided, and in the best constructions, furthermore, each mechanism, for reasons hereinafter referred to, will include two such weighted members which are rotated in opposite directions. Two such mechanisms are shown, but as their construction is identical but one will be described in detail. These mechanisms, being marked generally 34 and 35 in Figure 4, and the mechanism 35 will be described in detail. Referring to Figures 1, 2, 4 and 6, the mechanism includes a pair of rotary members 36, 37, shown in the form of wheels or discs, which are mounted on shafts 38, 39, hereinafter referred to. Each of these wheels supports a weight, marked 40, 41, this weight being located at a fixed predetermined distance from the axis of the wheel and being of a predetermined amount, depending on the extent of the vibratory movement desired. While an effective result can be obtained by the use of one unbalanced weighted wheel, two weighted wheels preferably are employed and where such construction is adopted the wheels will be driven so as to rotate in opposite directions, as by intermeshing gears 42, 43. Referring to the diagrammatic view of Figure 6, which is the preferred arrangement, assuming the lower wheel 37 is driven in the direction of arrow A, it will in turn, by means of the intermeshing gears 42, 43, drive the upper wheel 36 in the opposite direction, as indicated by the arrow B. With this arrangement, the centrifugal action produced in the lower wheel by the unbalanced weight will be down, and that of the upper wheel will be up, so that the two will balance each other and there is no tendency to produce a shaking action in a vertical direction. However, as the weighted parts of the wheels move toward the left, their centrifugal action will be combined on that side until they have passed their horizontal center position, when they both will be moving toward the right and will combine their centrifugal action on that side. Thus the full centrifugal action of the weights is obtained first to one side of the centers and then to the other in a horizontal direction, but with little or no tendency to have a vibratory action in a vertical direction. Thus a very even predetermined vibratory movement may be transmitted to the shaker frames 9, 10 through connections which will now be described. The two weighted wheels, where two are employed, are carried in a two part casing 44, 45, the parts of which are suitably secured together by bolts 46. This casing is supported on four rocker arms 47, 48, 49, 50, which at their lower ends are pivotally mounted in blocks 51, bolted or otherwise fixed to extension members 52, 53 secured to the stationary frame 7 before referred to, these extensions being strengthened by struts or braces 53'. At their upper ends, the rocker arms are pivotally secured to the casing sections on pivots 54, 55 mounted in extensions 56, 57 on the casing. The casing 44, 45 is rigidly connected with one of the shaker frames, as the frame 9, by a pair of rigid bars or rods 58, 59 securely held in place to the frame by bolts 60, and to the frame 9 by bolts 60'. It will be seen that with this construction the rocking action of the casing caused by the centrifugal motion of the unbalanced rotating wheels is transmitted to the shaker frames and the desired reciprocating movement of these frames is effected. The extent of this movement is readily and easily controlled by the springs 26, 27, and a very effective result is obtained. It will be observed that the flat springs 11, 12 supporting the shaking frames 9, 10 are substantially the same length as the rocker arms 47, 48, 49, 50 so that the vibrating or shaking movement will be substantially parallel, thus resulting in the desired even operation of the parts. The weights may be secured in the rotating members or wheels in any suitable manner. As shown, the wheels are recessed at 61 in Figure 2 to receive the weights. The wheels may be driven in any suitable manner. In the particular construction shown, where a plurality of vibrating or shaking mechanisms are employed, each such mechanism is provided with an independent driving means. As shown, the vibrating mechanism 34 is driven from a motor 62, and the vibratory mechanism 35 is driven from a motor 63. Referring to the mechanism 35, the shaft 39 of the wheel 37 is extended and has secured thereto a sheave or pulley 64 over which passes an endless cable 65, this cable also passing over idler sheaves or pulleys 66, 67 supported on shafts 68, 69 supported in brackets 70, 71 depending from the extensions 52, 53, before referred to, which support the casing. The cable also passes over a driving sheave or pulley 72 (Figure 1a) on the armature shaft 73 of the motor 63 which is preferably of the variable speed type. The vibratory mechanism 34 is driven in a similar manner and need not be further described. In the best constructions, a separate variable speed motor is employed for each vibratory unit, so that a different vibratory movement may be given to different sections of the frame. If desired, however, the different units may be driven 145

- from one motor by means of a shaft 74 and couplings 75, 76, in which arrangement the speed of both vibratory units will be the same.
- In Figures 7 and 8, two modifications of an unbalanced wheel arrangement are shown which may be employed under some circumstances. As shown in Figure 7, the wheels may be arranged side by side horizontally instead of vertically as in Figure 6, or they may be arranged as shown in Figure 8, with appropriate mechanism for driving them in different directions, as shown by the arrows. The particular mechanism selected to illustrate the invention is the shaking section of a Fourdrinier paper making machine as described, but it will be understood that the invention is adapted for use and may be used in other types or characters of mechanism having a shaking or vibratory part to which it is desired to impart a controlled shaking action.
- The invention has been shown and described in its preferred form. It will be understood, however, that one vibratory unit, or as many as may be desired, can be employed and that while two unbalanced rotary members preferably are used for each unit, one such member is within the invention. It will be understood therefore that various changes in the arrangement and construction of the parts may be made without departing from the invention as defined in the appended claims.
- What is claimed is:
1. In a paper making machine, the combination with a frame section mounted to have a shaking or vibratory movement, a rotary member provided with a weighted part arranged off center, means for rotating the member, and connections between the member and the frame section for effecting a vibratory or shaking movement of the latter.
  2. In a shaking mechanism, the combination with a frame section mounted to have a shaking or vibratory movement, unbalanced weighted means, means for giving the weighted means a rotary movement, and connections between the weighted means and the frame section, the weighted means being so arranged as to effect a horizontal vibrating movement of the frame section without any substantial vertical movement.
  3. In a paper making machine, the combination with a frame section mounted to have a shaking or vibratory movement, a wheel provided with a weighted portion arranged off center, means for rotating the wheel, and rigid connections between the wheel and the frame section for effecting a vibratory or shaking movement of the latter.
  4. In a shaking mechanism, the combination with a frame section mounted to have a shaking or vibratory movement, a pair of rotary members each provided with a weighted part arranged off center, means for rotating the members in opposite directions, and connections between the members and the frame section for effecting a vibratory or shaking movement of the latter.
  5. In a shaking mechanism for paper making machines, the combination of a frame section mounted to have a shaking or vibratory movement, a rotary member provided with a weighted part arranged off center, means for rotating the member, connections between the member and the frame section, and means independent of the member or its driving means for adjusting the amount of the vibratory movement imparted to the frame section.
  6. In a paper making machine, the combination of a vibratory frame section, a pair of rotary members each provided with a weighted part arranged off center, means for rotating the members in opposite direction, and rigid connections between the members and the frame section for effecting a vibratory movement of the latter.
  7. In a paper making machine, the combination of a vibratory frame section, a pair of rotary members each provided with a weighted part arranged off center, means for rotating the members in opposite directions, connections between the members and the frame section for effecting a vibratory movement of the latter, and means for controlling the extent of the vibratory movement.
  8. In a paper making machine, the combination of a support mounted to have a vibratory movement, a wheel having a weighted portion located off center, means for rotating the wheel, and connections between the wheel and the support.
  9. In a paper making machine, the combination of a support mounted to have a vibratory movement, a wheel having a weighted portion located off center, means for rotating the wheel, connections between the wheel and the support, and adjustable springs for controlling the vibratory movement imparted to the support.
  10. In a paper making machine, the combination of a support mounted to have a vibratory movement, a pair of wheels each having a weighted portion located off center, means for driving the wheels in opposite directions, connections between the wheels and the support, and adjustable springs for controlling the vibratory movement imparted to the support.
  11. In a paper making machine, the combination of a support mounted to have a vibratory movement, a plurality of spaced shaker mechanisms each including a rotary member having a weighted portion located off center, connections between the shaker mechanisms and the support, and means for driving the shaker mechanisms.
  12. In a paper making machine, the combination of a support mounted to have a vibratory movement, a plurality of spaced shaker mechanisms each including a rotary member having a weighted portion located off center, connections between the shaker mechanisms and the support, and means for driving the shaker mechanisms independently or simultaneously.
  13. In a paper making machine, the combination of a support mounted to have a vibratory movement, a plurality of spaced shaker mechanisms each including a rotary member having a weighted portion located off center, connections between the shaker mechanisms and the support, and means for driving the shaker mechanisms at different speeds.
  14. In a paper making machine, the combination of a frame section mounted to have a vibratory movement, a wheel having a weighted portion located off center, a casing in which the wheel is mounted, rigid connections between the casing and the support, and means for driving the wheel.
  15. In a paper making machine, the combination of a frame section mounted to have a vibratory movement, a wheel having a weighted portion located off center, a casing in which the wheel is mounted, pivotal supports for the casing, rigid connections between the casing and the support, and means for driving the wheel.
  16. In a paper making machine, the combination of a frame section mounted to have a vibratory movement, a pair of wheels each having a weighted portion located off center, a casing

in which the wheel is mounted, pivotal supports for the casing, rigid connections between the casing and the support, intermeshing gears on the wheels, and means for driving one of the wheels.

17. In a paper making machine, the combination with a shaking frame section, springs on which the section is mounted to have a vibratory movement, a casing, rigid connections from the casing to the frame, a pair of wheels mounted in the casing arranged to rotate in opposite directions and having weighted means cooperating therewith, pivotal supports for the casing, and means for driving one of the wheels.

18. In a paper making machine, the combination of a shaking frame section, springs on which the section is mounted to have a vibratory movement, a casing, pivoted arms of substantially the same length as the springs on which the casing is supported, connections between the casing and the frame, a pair of wheels mounted in the casing each having a weighted portion located off center, said wheels being ar-

ranged to rotate in opposite directions, and means for driving one of the wheels.

19. In a shaker section for paper making machines, a stationary support, a shaker frame, a wheel having a weighted portion arranged off center, means for driving the wheel, and connections from the wheel to the frame. 80

20. In a shaker section for paper making machines, a stationary support, a shaker frame, a pair of rotary members each having a weight located off center, said wheels rotating in opposite directions, connections between the wheels and the frame, and means for driving one of the wheels. 85

21. In a shaker section for paper making machines, a stationary support, a shaker frame, springs on which the frame is mounted in the support, a wheel having a weight located off center, connections between the wheel and the frame, means for driving the wheel, and adjustable springs between the support and the frame for controlling the movement imparted thereto by the wheel. 90
